UNITED STATES PATENT OFFICE.

CHARLES H. CLEVELAND, OF CADDO PARISH, LOUISIANA.

SUSPENDER-CLASP.

SPECIFICATION forming part of Letters Patent No. 231,999, dated September 7, 1880.

Application filed July 21, 1880 (No model.)

To all whom it may concern:

Be it known that I, CHARLES H. CLEVELAND, of Caddo parish and State of Louisiana, have invented certain new and useful 5 Improvements in Suspender-Clasps; and I do hereby declare that the following is a full, clear, and exact description of the invention, which will enable others skilled in the art to which it appertains to make and use the same, reference being had to the accompanying drawings, which form a part of this specification.

Figure 1 is a perspective view of a pair of suspenders equipped with my improved clasp. Fig. 2 is a detail view of the clasp detached, 15 and Fig. 3 is a detail view of a modification of my improved clasp.

In the several above-described figures corresponding parts are denoted by like letters of reference.

20 This invention relates to an improvement in suspender-clasps, which is especially adapted for and applicable to the improved suspenders for which Letters Patent of the United States were granted to myself on the 1st day of July, 25 1868, No. 80,142; and it consists, essentially, in providing such clasps (which are to be made of metal) with diagonal slots to receive the straps, which are thus caused to project in the exact direction or directions intended, substantially as I shall now proceed fully to describe 30 with reference to the drawings, in which—

A represents the suspenders, the lower converging ends of which are provided with clasps B, having at their upper ends diagonal slots C C, for the attachment of the said converging suspender-ends. The said clasp is provided 35 with a vertical eye-slot, D, to receive the but-

ton E upon the lower clasp, F. This latter clasp is provided with two diagonal slots, G G, and one horizontal slot, H, to receive, respectively, the diverging straps I I, having button-holes for attachment to the pantaloons-buttons, and the strap J, having a button-hole or other suitable means for attachment to the drawers of the wearer.

40 From the foregoing description the operation and advantages of my invention will be readily understood. The suspender ends and straps are readily attached in the diagonal slots of the clasps from which they project in 45 the exact direction required, thus insuring convenience, strength, and comfort.

50 Instead of the slot-and-button fastening shown in Fig. 3, a hook-and-slot fastening may be used between the clasps, as shown in Fig. 55 3 of the drawings.

Having thus described my invention, I claim and desire to secure by Letters Patent of the United States—

60 As an improvement in suspender-clasps, the combination, with the upper clasp, B, having diagonal slots C C, of the lower clasp, F, having diagonal slots G G and horizontal slot H, located between the lower converging ends of said slots G, the two adapted to be connected, 65 substantially as and for the purpose set forth.

In testimony that I claim the foregoing as my own I have hereto affixed my signature in presence of two witnesses.

CHARLES H. CLEVELAND.
